United States Patent Office.

NIELS POULSON, OF NEW YORK, N. Y.

Letters Patent No. 92,356, dated July 6, 1869.

IMPROVEMENT IN STAIRS.

The Schedule referred to in these Letters Patent and making part of the same.

To all whom it may concern:

Be it known that I, NIELS POULSON, of New York city, county of New York, and State of New York, have invented a new and useful Improvement in Stairs; and I do hereby declare the following to be a full, clear, and exact description of the same, reference being had to the accompanying drawings, in which—

Figures 1 and 3 are side elevations, partly in section.

Figures 2 and 4 are plan views, partly in section.

Figure 5 is a transverse vertical section of a casing for a tread consisting of one plate.

Figure 6 is a transverse vertical section of a casing or receptacle for a tread, the front edge or nosing of which is adjustable.

The same letters of reference, where employed in the different figures, denote identical parts.

The nature of my invention consists in constructing stairs in such a manner that the treads consist of a hollow casing or receptacle, into which any suitable material of composition or matter may be placed. When said material or composition of matter is worn out or decayed, it may easily be removed and replaced, without any injury to the staircase.

To enable others to make and use my improvement, I will proceed to describe its operation and construction.

Fig. 5 represents a transverse vertical section of a tread, and illustrates at once my invention.

A is a plate, made of cast-iron or any other suitable material. At its front edge it is curved upward, as shown in fig. 5, at A¹, and at its rear side and ends it is bent at a right angle, and extends upward until it reaches the upper face of the tread. The recess thus formed is filled with some suitable material or composition of matter, which is not easily worn or decayed. Concrete, asphaltum, terra-cotta, tiles, stone, or marble tiles, cork, wood, or any other suitable material, (fire-proof is recommended,) may be used, according to the notion of the builder.

Figs. 2 and 4 show different designs of patterns for treads, and my invention enables the builder to choose the material or composition that may harmonize with the walls or floors of the halls in which the stairs are to be placed.

Fig. 1 represents a side elevation of exterior stairs, and fig. 3 is a side elevation of interior stairs.

My improvement may be used with advantage as well for exterior as interior stairs, and is not confined to iron, but may be used in any kind of stairs.

If desired, the panels and risings may be ornamented, in same manner as the treads of the stairs, with inlaid filling.

The casing or receptacle for the tread may either consist of one or more pieces, and so constructed that the front edge or nosing A¹ may be made adjustable, so as to be removed and replaced by another when worn out. (See fig. 6.)

In figs. 1 and 5, the casing or receptacle for the tread A³ is constructed with an uneven inner surface, so that the concrete will more readily adhere to it.

In the same figures the casing A⁴ is, at its inner surface, provided with projections, cast to the plate A, in order to keep the material or composition of matter with which it is filled in its place. For such projections a a a a, nails, hooks, or bolts may be used. If desired, the heads of bolts may rest on or in the material or composition constituting the tread, and passing through the plate A, be fastened to the bottom or lower surface of plate A.

I do not confine myself to any of the above devices, which may be varied indefinitely.

When the casing for the tread is to contain any material which does not necessitate such projections, its inner surface may be made smooth, as shown in figs. 1 and 5, at A⁵.

The casings or receptacles for the treads may be filled and finished before the stairs are put up.

Having thus described my invention,

What I claim, and desire to secure by Letters Patent, is—

A hollow casing or receptacle, into which any suitable material or composition of matter may be placed, serving as treads or platforms for stairs, constructed and arranged substantially as and for the purpose set forth.

In testimony whereof, I have signed my name to this specification, in the presence of two subscribing witnesses.

NIELS POULSON.

Witnesses:

ANTHONY WARNER,
CARL GERNOL.
